UNITED STATES PATENT OFFICE.

JAMES J. TRACY, OF CLEVELAND, OHIO.

APPARATUS FOR DYEING AND THE LIKE.

1,174,912.

Specification of Letters Patent.

Patented Mar. 7, 1916.

Application filed March 12, 1914. Serial No. 824,126.

To all whom it may concern:

Be it known that I, JAMES J. TRACY, a citizen of the United States, and a resident of Cleveland, county of Cuyahoga and State of Ohio, have invented a new and useful Improvement in Apparatus for Dyeing and the like, of which the following is a specification, the principle of the invention being herein explained and the best mode in which 10 I have contemplated applying that principle, so as to distinguish it from other inventions.

The present improvements relate, as indicated, to apparatus intended for use in 15 dyeing operations and the like, the apparatus being intended for use in suitably handling a container or cage adapted to receive the materials to be dyed or otherwise treated in a vat or tub. In dyeing, 20 washing, or bleaching operations, and in analogous situations, it is desirable either that the material be moved about in the solution to secure a complete and thorough treatment of all parts of the material, or 25 that the solution be forced through the material. The present machine has been designed primarily for operation along the first-named lines, namely, by moving the material about in the solution, although it 30 also secures a certain movement of the solution in and about the container which materially assists in securing the results desired.

A further object of the invention is the 35 provision of an efficient apparatus involving the use of a number of vats each being adapted to receive a suitable container together with means for simultaneously operating all of any desired number of such 40 containers in the vats. Particular attention has also been paid to the construction of the container, and the forms here illustrated are particularly efficient in securing a thorough 45 action of the solution upon all parts of the material, the containers being provided with means which prevent the bunching of the material therein and cause the material to move loosely about in the container during 50 movement of the same. To the accomplishment of the foregoing and related ends, said invention, then, consists of the means hereinafter fully described and particularly 55 pointed out in the claims.

The annexed drawings and the following 55 description set forth in detail certain mechanism embodying the invention, such dis-

closed means constituting, however, but one of various mechanical forms in which the principle of the invention may be used.

In said annexed drawings: Figure 1 is 60 a side elevation of the present apparatus; Fig. 2 is a plan view of the same; Fig. 3 is a view in perspective of one form of the container or cage; Fig. 4 is a side elevation of the same; Fig. 5 is a plan view 65 indicating diagrammatically one arrangement of the partitions in such container; Fig. 6 is a side elevation showing the locking clasp for the cover of the container; and Figs. 7, 8 and 9 are views similar to 70 Fig. 5, showing various modified forms of containers.

It will be understood that any desired 75 number of vats may be used, although I have here illustrated but three of these elements. In Figs. 1 and 2 there are shown three aligned vats 1, 2 and 3, such vats being preferably of cylindrical form and being vertically disposed. Connected to the interior of each of said vats are water and 80 steam supply pipes 4 and 5 for the purpose of supplying the solution to the vats and for the purpose of heating the same. In each of such vats there may be placed a container 85 in the form of an open cage or basket 6 such as is best shown in Figs. 3 and 4. This container 6 is preferably provided with an open frame 7 covered with foraminous material, preferably in the form of a coarse wire screen, the container being cylindrical 90 in shape, and, when placed in the vat, having its outer walls spaced a few inches from the walls of the vat. The foraminous covering may be of either wood or metal, depending usually upon the operation to be 95 carried on in the apparatus, and may be a wire screen or perforated metal plate, or in other cases may consist of spaced wooden slats. The frame of the container 6 includes two vertical diametrically opposite 100 uprights 8, to the centers of which are pivotally attached the ends of the loop or bail 9 which passes up over the top of the container. To the top of this bail 9 there is attached a U loop 10 which is adapted to 105 be engaged by a hoist 11 mounted upon a suitable trolley or trackway 12 disposed above the aligned vats. By means of this mechanism it is possible to conveniently remove the containers from the vats and to 110 transport the same from one vat to another.

Loosely mounted about the sides of the bail

9 are U-shaped clips 13 which are adapted when pressed against the bail to extend past the sides of the upright, thus locking the bail in the position shown in Fig. 3. These 5 clips are removably held in this position by means of bolts or set-screws 14. The container is provided with a horizontally disposed partition 15, of coarse wire or similar material, thus dividing the container into 10 two compartments or chambers 16 and 17. In this way it is possible to treat a greater amount of material than can be efficiently treated in a single compartment container of equal volume, since the material is now 15 separated into two parts and does not bunch up and prevent a thorough contact of the solution with all parts of the material. The container is provided with covers 18 at either end, such covers being formed in two 20 portions and being pivoted to open and permit of the removal of the material therein. It will be obvious that the material can be dropped out of either compartment by merely unfastening the U-shaped clips 13 25 and turning over the container in the bail. Any suitable fastening means may be provided for the covers 18, one effective and simple form being illustrated in Fig. 6. In this device a U-shaped channel 40 is attached to the inside of one of the frame members of the container and is adapted to receive therein the edge strand 41 of the cover, when the latter is closed. Alined 30 apertures are formed in the two sides of 35 the channel and in the upright of the container frame and through these apertures is passed a clasp 42 which is preferably made of resilient wire and serves to maintain the cover in its closed position.

40 The specific construction of the aforesaid container forms the subject matter of a separate application filed February 7, 1916, Serial No. 76,510, claims to this feature of the apparatus having been required to be divided out of the present case.

45 Disposed about the upper or open end of each vat are circular tracks 19 mounted concentrically with respect to the vats, such tracks being adapted to support rollers 20 50 carried in two laterally extending arms 21 attached to the bail 9 or upper portion of the framework 7 of each container. These arms can readily be attached to the sides of the bail by rivets 43 (see Fig. 4) or in some 55 other equally simple manner. In Fig. 3 the container is shown without the arms 21. The construction and disposition of these arms can best be seen in Fig. 2, and it will be noticed that the end of each arm is pro- 60 vided with a slot 22 the disposition of which is substantially radial with respect to the container and vat. When the container 6 is lowered into the vat by the hoist 11 it is placed in such position that the rollers 20 65 on the arms 21 engage the track 19 about the

vat, the container thereupon being supported from such track and being freely rotatable within the vat but without the necessity of providing any support within the solution itself.

70 Disposed along either side of such alined vats are trackways or guides 23 mounted upon suitable standards 24 at substantially the elevation of the top of the vat. Reciprocably mounted in these guides 23 are members 25 provided adjacent to each vat with an upstanding pin 26, such pin loosely engaging in the slot 22 in the end of each arm 20. These members 25 are reciprocated in opposite directions simultaneously and the 75 effect of this operation upon the containers in the vats will be readily apparent, the containers being oscillated through a distance equal to the travel of the reciprocating members 25 which are driven by suitable connecting rods 40 attached to cranks 27 driven by a transversely disposed shaft 28 which in turn may be driven by any suitable means, there being here shown a second transverse shaft 29 which will preferably be operated 80 from an electric motor or by means of a belt and pulley from some suitable source of power. Any other suitable driving mechanism may obviously be employed for reciprocating the members 25. This oscillatory movement which is given to the containers 6 causes the solution in the vats to move through and around the material held in the containers, and this action is increased 85 by the provision in each container of a vertical solid partition 30 such as is shown in Fig. 4. During the oscillatory motion of the container this partition acts to stir up the solution, producing currents therein 90 which cause the liquid to pass through all parts of the container and to thus reach and treat all of the material held therein. The precise construction and disposition of this transverse vertical partition is of relative 95 unimportance, and it may be formed as 100 shown in Fig. 5 where two short partitions 31 extend radially inward from diametrically opposite points of the container, while a central partition 32 is disposed at right angles to the two short partitions 31. Similarly, the construction shown in Fig. 7 may 105 be used, in which two vertical partitions 32 are used, one extending from the bottom of the container to the horizontal partition, and the other extending from the horizontal partition to the cover and being disposed at an angle, preferably a right angle, to the lower partition. An increased movement 110 of the liquid through the container may be had by providing curved tangentially ex- 115 tending fins or vanes 35 about the circumference of the container. Such a construction is shown in Fig. 8, while in Fig. 9 a 120 modification of the same is illustrated, there being in this latter type a vertically disposed 125 130

circular wire cylinder 36 in the center of the container, and there being two inwardly extending curved solid vanes 37 attached to the inside of such wire cylinder.

5 It will be understood that at any time one of the containers 6 may be removed from its vat by means of the hoist 11, and transported to another vat or the material therein removed for drying. Any desired number of 10 containers may be operating simultaneously, each being given the same oscillatory movement and each vat producing the desired dyeing or washing effect, upon the material therein, thus providing a uniform treatment 15 of the material in each of the vats through a given length of time, although of course in dyeing cloth certain colors a longer treatment is necessary in some cases, and at such times the containers may be oscillated in 20 the vats during a longer period.

By means of the solid partitions disposed in the various ways in the containers a certain movement of the cloth with respect to the liquid is secured. Without the use of 25 such vertical partitions the material in the solution would tend to move with the solution, and there would be little, if any, movement of one relative to the other. It is, of course, highly desirable to provide a certain 30 amount of movement of either the solution through the cloth or the cloth through the solution, and this is secured by means of these partitions. Upon movement in one direction the partition forces the solution 35 before it, a certain amount of this solution tending to move toward the wall of the container. The material, on the other hand, is not moved as rapidly as the solution and tends, by reason of its own inertia, to move 40 slower than the solution, thus causing a relative movement between the two. Similarly the fins or vanes attached to the container operate to drive into the center of the same, during movement in one direction, a certain 45 amount of liquid which, upon reverse movement, flows out between the vanes thus causing an internal circulation in the container, which is of great value in producing an even effect of the treatment upon the material 50 held therein.

Other modes of applying the principle of my invention may be employed instead of the one explained, change being made as regards the mechanism herein disclosed provided the means stated by any of the following claims or the equivalent of such 55 stated means be employed.

I therefore particularly point out and distinctly claim as my invention:—

60 1. In a dyeing machine, the combination of a plurality of alined vats, a container removably supported in each of said vats, and operating means adapted to detachably engage each of said containers and oscillate 65 the same about a vertical axis.

2. In a dyeing machine, the combination of a plurality of alined vats, a container removably and oscillatorily supported in each of said vats, and members disposed on either side of said vats and reciprocating in opposite directions, said containers being loosely connected to said members, and being oscillated by the movement of the same. 70

3. In a dyeing machine, the combination of a plurality of alined vats, a container removably and oscillatorily supported in each of said vats, parallel members mounted on either side of said alined vats and reciprocating in opposite directions, and means loosely connecting said containers to said 80 members, whereby said containers are oscillated by such movement of said members. 75

4. In a dyeing machine, the combination of a plurality of alined vats, a container removably and oscillatorily supported in each of said vats, parallel members mounted on either side of said alined vats and reciprocating in opposite directions, said members being provided with pins disposed opposite each of said vats, and laterally extending 90 arms attached to said containers, said arms being provided with slots adapted to receive such pins, whereby said containers are oscillated by such movement of said containers. 95

5. In a dyeing machine, the combination of a plurality of alined vats, a circular track disposed about each of said vats, a container removably received in each of said vats, said containers being rotatably supported upon said tracks, and operating 100 means adapted to detachably engage said containers and oscillate the same. 105

6. In a dyeing machine, the combination of a plurality of alined vats, a circular track disposed about each of said vats, a container removably received in each of said vats, said container being provided with laterally extending arms bearing rollers resting on said track, said arms having slots therein, parallel members mounted on either side 110 of said alined vats and reciprocating in opposite directions, and pins mounted on said members opposite said vats, said pins being loosely engaged in such slots, whereby said containers are oscillated by such movement of said members. 115

7. In a dyeing machine, the combination of a vat, a foraminous container oscillatorily supported therein, and a partition in said container disposed at right angles to the 120 plane of oscillatory movement of said container.

8. In a dyeing machine, the combination of a vat, a foraminous cylindrical container oscillatorily supported in said vat to oscillate about a vertical axis, and a vertical partition mounted in said container. 125

9. In a dyeing machine, the combination of a cylindrical vat, a foraminous cylindrical container oscillatorily supported in said 130

- vat to oscillate about a vertical axis, a vertically disposed central partition in said container, and a second partition attached to said container and also disposed vertically.
- 5 10. In a dyeing machine, the combination of a vat, a container removably supported in said vat and out of contact with the same, and operating means adapted to detachably engage said container and oscillate the same in said vat.
11. In a dyeing machine, the combination of a vat, a track mounted adjacent thereto,

a container supported from said track and received in said vat, said container being out of contact with said vat, and operating 15 means adapted to detachably engage said container and oscillate the same in said vat.

Signed by me, this 9th day of March, 1914.

JAMES J. TRACY.
